UNITED STATES PATENT OFFICE.

RALPH E. MARBURY, OF EDGEWOOD PARK, PENNSYLVANIA, ASSIGNOR TO WESTINGHOUSE ELECTRIC & MANUFACTURING COMPANY, A CORPORATION OF PENNSYLVANIA.

GRID LEAK FOR RADIO APPARATUS.

Application filed January 24, 1921. Serial No. 439,360.

This invention relates to resistance units, more especially to devices which are particularly adapted for use as grid leaks for radio apparatus and having resistances 5 which vary from about 100,000 ohms to 10 megohms.

Resistance units, especially low priced units, for use as grid leaks, are in considerable demand in radio apparatus. Heretofore, several types of grid leaks were proposed, such units consisting of small strips 10 of fibrous sheet material, usually paper, about one inch long and one-eighth to one-quarter inch wide. The material was coated 15 with various substances having relatively high resistance, such as india drawing ink, and then dried.

Since it is rather difficult to obtain coated materials of this type having uniform resistance, on account of varying drying conditions, it was necessary to adjust each individual grid leak by connecting the same to a Wheatstone bridge arrangement and to remove, with an eraser, a portion of the 20 surface resistance material until the resistance of the unit was raised to the desired value. Since the conductor was composed of a comparatively small number of particles having good conducting properties making loose 25 contact with one another, the unit was relatively unstable, and a slight disturbance of the surface of the material resulted in a large change in resistance, often several hundred percent.

My invention is designed to obviate this disadvantage, it being among the objects thereof to device a resistance unit adapted 30 for grid leaks which is simple in construction, and the resistance of which does not change.

In practising my invention, I provide a resistance unit in which the conducting particles are large in number and are connected in parallel. Such an arrangement of particles makes the unit stable and also makes 35 it possible to use a material having a high resistance per unit area. More specifically, I form a resistance unit by providing a thin, porous sheet of paper which is impregnated 40 with suitable resistance material and placing strips of foil, in parallel along the edges thereof, the outer edges of the strip extending beyond the edges of the paper, and their inner edges being spaced apart. The assem-

bly is rolled to form a rod which is then 55 compressed, the ends of the foil being perforated to form terminal connections for the unit.

In the accompanying drawing constituting a part hereof and illustrating a single 60 embodiment of my invention,

Fig. 1 is a perspective view of the material, from which my resistance unit is formed, in the process of being rolled;

Fig. 2 is a perspective view showing the 65 treatment and the relative positions of the parts;

Fig. 3 is a plan view of the completed resistance unit, and

Fig. 4 a side view thereof.

I provide a mandrel 1 upon which is placed a roll of suitable fibrous sheet material, such as a thin, porous, tissue paper 2. I provide also a mandrel 3 upon which are mounted two rolls 4 and 5 of foil, generally 75 copper, tin or aluminum, the foils being spaced apart and the outer edges thereof extending an appreciable distance beyond the edges of the sheet 2 of paper. I further provide a tank 6 containing a solution of 80 resistance material, such as a solution of india drawing ink or, preferably, a colloidal solution 7 containing silver nitrate and shellac. Rollers 8 and 9 are rotatably mounted in tank 6, a suitable distance below the 85 surface of the solution 7.

The paper 2 is passed over rollers 8 and 9 and wound on mandrel 10, becoming impregnated with the resistance material 7 in its passage through the tank 6. If desired, 90 the impregnated sheet material may be passed through a drying tower (not shown) before being rolled upon mandrel 10, the silver being precipitated by exposure to light before the sheet material is rolled on the 95 mandrel. The parallel sheets of foil 4 and 5, the outer edges of which extend beyond the edges of sheet 2, are rolled therewith upon mandrel 10.

When a suitable number of turns have 100 been rolled on the mandrel, the assembly is cut away, the mandrel removed and the assembly compressed to flatten it, as shown in Figs. 3 and 4. It is then baked under slight pressure to harden the shellac in the 105 impregnating mixture and hold the various laminations together. The final adjustment of the resistance unit may be made by

placing the same in a Wheatstone bridge arrangement, unwinding the proper number of turns and removing them until the desired resistance is obtained.

5 By reason of the large surface area and the high resistance-per-unit area, the number of turns does not have to be very accurate, and the adjustments made in the Wheatstone bridge will not cause critical 10 changes of resistance. The removal of more or less of the material than is necessary to give a certain final resistance value does not appreciably change the resistance of the entire unit.

15 After the adjustment is made, the unit is dipped in shellac and baked to harden the same, giving a structure which is protected from the atmosphere and which does not change in resistance when subjected to exterior disturbances. The unit may be 20 placed in a suitable holder, being held in place by screws 13 and 14 extending through openings 11 and 12 in the flattened ends of the metal foils.

25 It is obvious that my invention may be practised by various modifications of the method I have above described, and I do not confine myself to the steps enumerated or to the materials used. It is obvious that 30 various forms of resistance units may be made embodying the principles laid down herein.

I claim as my invention:

1. A resistance unit comprising a plurality of strips of foil and material having high resistance interposed therebetween and rolled to form a unit.

2. A resistance unit comprising a rolled sheet of fibrous insulating material and strips of foil placed longitudinally thereof, 10 said strips being separated, said sheet of insulating material carrying a finely divided conducting material.

3. A resistance unit comprising a rolled

sheet of fibrous insulating material and a 45 strip of foil at each edge of said sheet, the outer edges of said foils extending beyond the edges of said sheet and the inner edges thereof being separated, said sheet of insulating material carrying a finely divided 50 conducting material and a binding material.

4. A resistance unit comprising a rolled sheet of fibrous insulating material, a strip of foil at each edge of said sheet, the outer edges of which project beyond the edges of 55 said sheet and the inner edges of which are separated, and conducting material within said sheet.

5. A resistance unit comprising a rolled sheet of fibrous insulating material, a strip 60 of foil at each edge of said sheet, the outer edges of which project beyond the edges of said sheet and the inner edges of which are separated, and finely divided metal within 65 said sheet.

6. A resistance unit comprising a rolled sheet of fibrous insulating material, a strip of foil at each edge of said sheet, the outer edges of which project beyond the edges of 70 said sheet and the inner edges of which are separated, and finely divided silver within in said sheet.

7. A unit having high resistance and comprising a fibrous body having laminar end terminals embedded therein, said fibrous 75 body being impregnated with a finely divided conducting material.

8. A unit having high resistance and comprising a body of composite material and laminar end-terminal conductors embedded 80 therein and separated from each other, said composite material comprising a finely divided conducting material and an insulating material.

In testimony whereof, I have hereunto 85 subscribed my name this 17th day of January, 1921.

RALPH E. MARBURY.
